UNITED STATES PATENT OFFICE.

RICHARD P. KRONKE, OF MERIDEN, CONNECTICUT.

TUG-LOOP.

1,088,908.

Specification of Letters Patent. Patented Mar. 3, 1914.

Application filed June 14, 1913. Serial No. 773,618.

To all whom it may concern:

Be it known that I, RICHARD P. KRONKE, a citizen of the United States, residing at Meriden, in the county of New Haven and State of Connecticut, have invented a new and useful Improvement in Tug-Loops; and I do hereby declare the following, when taken in connection with the accompanying drawings and the characters of reference marked thereon, to be a full, clear, and exact description of the same, and which said drawings constitute part of this application, and represent, in—

Figure 1 a side view of a tug loop constructed in accordance with my invention. Fig. 2 an edge view of the same. Fig. 3 an inside view of one of the members detached. Fig. 4 a sectional view on the line *a—b* of Fig. 1. Fig. 5 a sectional view on the line *c—d* of Fig. 1. Fig. 6 a perspective view of the tuck loop, detached.

This invention relates to an improvement in tug loops, and particularly to metal loops having a lining and with which a buckle is attached, the object of the invention being to provide a loop the metal parts of which may be conveniently cast and with which the buckle and tuck loop may be firmly connected; and the invention consists in the construction hereinafter described and particularly recited in the claim.

The loop proper is formed in two parts 2 and 3 each having the usual thill opening around which are channels 4 and 5 to receive the edges of a lining 6 of rubber, leather or other suitable material. At the upper end of each member a long slot is made forming spring-fingers 7, and extending from the slots into the upper ends 8

are circular notches 9 to receive the bar 10 of a buckle 11 this bar being inserted between the ends 8 and the spring-fingers 7. The slots forming the fingers 7 also provide for the location of a tuck loop 12 which is preferably rectangular in cross-section, and this tuck loop and the buckle are secured in place by screws 13 passing through the ends of the fingers into the upper ends of the members 2 and 3. This tuck loop serves to hold the upper ends of the loop together. The lower ends are connected together by a screw or rivet 14 with the ends of which are connected arms 15 and 16 of a girth bar 17. The parts are thus firmly connected together and the lining secured in place. In this construction the parts are readily assembled, and when assembled are firmly united.

I claim:—

A tug loop comprising two members formed in adjacent faces with grooves, a lining the edges of which are located in said grooves the upper ends of the members formed with slots providing spring-fingers, the upper ends of the members formed with notches opening into said slots, a buckle located in said notches, a tuck loop inclosing said spring-fingers, means for connecting the outer ends of the spring-fingers with the members, and means for connecting the lower ends of the members.

In testimony whereof, I have signed this specification in the presence of two subscribing witnesses.

RICHARD P. KRONKE.
